CLAIM

The ornamental design for a combined handbag and detachable fitted clutch, as shown and described.

DESCRIPTION

FIG. 1 is a front perspective view of a combined handbag and detachable fitted clutch, showing my new design;

FIG. 2 is a right side elevational view;

FIG. 3 is a rear perspective view thereof in an open condition; and

FIG. 4 is a front perspective view showing the clutch partially removed.

The bottom of the handbag is substantially plain and unornamented.

FIG. 4
